UNITED STATES PATENT OFFICE.

CHARLES STICHLER, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

SELF-HEATING SAD-IRON.

1,242,489.

Specification of Letters Patent.

Patented Oct. 9, 1917.

Application filed January 20, 1915. Serial No. 3,227.

To all whom it may concern:

Be it known that I, CHARLES STICHLER, a citizen of the United States, and a resident of Philadelphia, county of Philadelphia, State of Pennsylvania, have invented a certain new and useful Improvement in Self-Heating Sad Irons, of which the following is a specification.

My invention relates to self-heating sad irons in which a gaseous fuel is used as the heating medium and has for its object to simplify and improve the construction of such irons and to increase the efficiency thereof. My improvement will be fully described hereinafter and the features of novelty will be pointed out in the appended claims.

Reference is to be had to the accompanying drawings in which Figure 1 is a longitudinal section of my improved sad iron; Fig. 2 is a plan view thereof with the cover removed; Fig. 3 is a horizontal section looking upward and taken on the line 3—3 of Fig. 1; Figs. 4 and 5 are cross sections on the lines 4—4 and 5—5 respectively of Fig. 2; Fig. 6 is a longitudinal section of another form of my improved sad iron; Fig. 7 is a plan view thereof with the cover removed; Fig. 8 is a similar view with burner removed from the body; and Figs. 9 and 10 are cross-sections taken respectively on the lines 9—9 and 10—10 of Fig. 7.

In the drawings 1 represents the body of the iron, said body being hollow and provided with a bottom preferably having an intermediate portion 2 which is relatively thicker than the adjacent end portions thereof and its rear edge preferably curved as indicated at 3 in Fig. 2. The upper edges of the side walls of said body are formed with a plurality of recesses 4 which form outlets for the products of combustion when the body is closed by means of the cover 5. The latter may be movably secured upon the body 1 in any suitable manner and as illustrated is provided at its front end with an elongated opening 6 adapted to receive a hook 7 projecting upwardly from the body at the apex thereof, and arranged to extend over the upper surface of the cover in a rearward direction. At its rear end the said cover 5 is provided with a rearwardly open slot 8 for the accommodation of the shank or stem 9 when the parts are in operative connection, said shank or stem having a

screw threaded engagement with the body 1 and being secured to or forming part of the locking lever 10. The latter is provided with horizontal shoulders 11 and 11^a adapted to be moved over and into engagement with the upper surface of the cover as the lever 10 is manipulated, that portion of the surface of said cover 5 which is adjacent to the slot 8 and adapted to be engaged by the shoulder 11 being inclined or curved upwardly toward the front of the iron in the preferred construction as indicated at 12 in Figs. 1 and 6. Thus the lever 10 is moved in the arc of a circle to cause the shoulders 11 and 11^a to extend transversely across the slot 8 the stem 9 owing to its screw-threaded engagement with the body 1 will draw the said shoulders 11 and 11^a downwardly and finally firmly clamp the rear end of the cover 5 on the body 1. During this actualization of the locking lever 10 as described the shoulder 11 will engage the inclined portion 12 and will exert a camming action thereon tending to force the said cover forward and beneath the hook 7 whereby the front end 70 of said cover is securely locked in position. With this arrangement both ends of the cover are firmly secured in operative connection with the body and the danger of locking the rear end of said cover while the forward 80 end thereof is unintentionally left unsecured is obviated.

The cover 5 is of a size and shape to properly close the upwardly open body and at the same time to leave the recesses 4 entirely free and unobstructed for the escape of the combustion products.

In order that the iron may be readily manipulated and the cover moved to and from its closed position relatively to the body 1 I provide a handle 13 preferably constructed of wood or other material which is a poor conductor of heat and carried for instance by a support 14 of substantially U-shape as shown in Fig. 1. The said support 14 may be connected with the cover 5 in any suitable manner as for instance by means of a single screw 15 extending through said support into a boss 16 formed on said cover and which in addition serves to space said support from the cover and thus reduces the degree of heat which is communicated from said cover to the support and to the handle by conduction. In order to maintain said handle 13 in proper alignment with the 100

longitudinal axis of the iron and to prevent it from rotating about said screw 15 as an axis, I provide said cover 5 for instance with spaced lugs 17 extending upwardly therefrom in pairs at opposite side edges of said support 14 and forming recesses in which the latter is seated when the screw 15 is firmly connected with the boss 16. In some cases a single pair of lugs 17 forming a single recess for the accommodation of the support 14 may be found sufficient for the intended purpose.

The burner which is shown in Figs. 1 to 5 inclusive in combination with the body comprises a hollow chamber or shell 18 adapted for connection with a source of fuel supply through the medium of the customary Bunsen tube 19 provided with the usual nipple 20 for the accommodation of the well known flexible tube or hose. The Bunsen tube 19 is preferably detachably connected with the shell 18 in order to facilitate the assembling of the parts and extends through a suitable opening 21 in the rear wall of the body. The forward end of the shell 18 extends transversely across the longitudinal axis of the body 1 and is covered by means of a plate 22 detachably secured in position in any suitable manner as by means of a screw 23 connected with a bridge piece 23^a extending vertically across the shell 18, said plate 22 being provided with jet apertures 24 which project toward the front or apex of the iron. The front end of the shell is inclined so that the plate 22 when in position to cover the same will be disposed at an acute angle relatively to the bottom of the body 1 with the result that the jet apertures 24 will always be directed toward the inner surface of the said bottom of the iron. A pair of members 25 curved to substantially fit along the inner surfaces of the side walls of the body 1 extend forwardly from the shell 18 and are connected together at their front ends by means of a transverse plate 26, the shell 18, members 25 and plate 26 being preferably cast or otherwise constructed in one piece to form an intermediate space 27. In the operative conditions of the iron the plate 26 rests upon lugs 28 formed on the inner surfaces of the side walls whereby the forward end of the burner is supported in position, the rear end thereof being supported by the Bunsen tube 19 as shown in Fig. 1. The plate 26 is provided with an elongated slot 29 through which the shank of a screw 30 is arranged to extend into screw threaded engagement with a projection 31 projecting upwardly from the bottom of the iron, the head of said screw being arranged to bear upon said plate 26 whereby said forward end of the burner is securely fastened in operative position. The elongated slot 29 permits an adjustment of the burner in a lengthwise direction to se-

ure a proper coöperation between the parts at all times. The projection 31 is pointed or wedge shaped toward the rear of the body for the purpose of reducing resistance to the travel of the heat toward the front of the iron to a minimum.

When it is desired to use the iron the Bunsen tube 19 is first connected with a source of fuel supply through the medium of the usual flexible tube or hose having one end slipped over the nipple 20. The fuel will pass through the tube 19 into the shell or chamber 18 and out through the apertures 24 where it may be ignited in any suitable manner as by passing a lighted match, taper or other igniting medium through the space 27, it being understood that the cover 5 is in an open position and is brought to a closed position after ignition has taken place. After being ignited the flames will be directed toward the apex and bottom of the iron owing to the direction in which said apertures extend and the inclination of the plate 22 and front end of the shell 18 and will contact with the relatively thickened portion 2 of the bottom of the iron. This thickened portion 2 takes longer to heat than the adjacent thinner parts of said bottom which are at a distance from the flames and by conduction heats said thinner parts so that an operative and effective degree of heat is produced in all parts of the bottom at approximately the same time and the said bottom is evenly heated throughout its entire extent.

In order to confine the heat in close proximity to the bottom of the iron and to prevent same from escaping upwardly through the space 27 I provide a closure 32 which is adapted to fit or set into said space and as shown preferably depends from the cover 5 so that when the latter is in its closed position the closure 32 will be located in said space 27 and completely fill the same. The rear wall of said closure 32 is preferably beveled vertically and curved laterally to fit a correspondingly shaped portion of the shell 18 as shown in Figs. 1 and 3. The said closure may be secured to the cover in any suitable manner as by means of a nut 15^a fitted upon the end of the screw 15 which in this case projects through the cover and through said closure 32 which latter may be provided with a recess for the reception of said nut 15^a to secure a flush construction. With this arrangement a complete surface is formed in front of the burner shell 18 whereby the heat generated by the flames at the jet apertures 24 is confined in close proximity to the bottom of the iron and thus exerts a heating effect thereon in a maximumly effective manner. In the above construction the products of combustion pass along the bottom beneath the surface formed by the members 25, plate 26

and closure 32 over the entire bottom toward the front of the iron and out through the space α between the forward end of the burner and the apex of the iron and finally escape to the atmosphere through the recesses 4. The air necessary to promote and sustain combustion is drawn into the body through the rearmost recesses 4 and passes to the flames at the jet apertures through the spaces β between the shell 18 and the walls of the body 1. In this manner the necessity for special inlets for the air is done away with and the cost of manufacture of the iron as a whole is materially reduced without affecting its efficiency. The said closure in addition to the functions described may also be utilized to add weight to the iron and by being detachably secured to the cover may be replaced by other closures so that the weight of the iron may in this manner be readily adjusted to meet different circumstances. By detachably connecting the plate 22 with the shell 18 the said plate may be replaced by others having jet apertures of different sizes or in different arrangements so that said burner may be used in a maximumly effective manner with gases of varying kinds. The removable plate also permits the jet apertures and the interior of the shell 18 to be easily cleaned from time to time whereby the said burner may at all times be maintained in a condition of maximum efficiency. The bridge piece 23^a serves to break the force of the fuel coming from the tube 19 and divides the same and distributes it in the shell 18 whereby said fuel is prevented from directly rushing through the jet apertures 24 thus making the burner substantially noiseless and obviating waste of fuel. The burner may be readily removed from the body by simply first disconnecting the Bunsen tube 19 therefrom and then removing the screw 30 after which said burner is free to be lifted from said body 1 for any purpose. This form of my improved burner is extremely light in weight and comprises no intricate parts likely to become disarranged.

As shown in Figs. 6 to 10 inclusive the front end or apex 1^a of the hollow body 1 preferably inclines rearwardly and the side walls 1^b thereof preferably converge upwardly as illustrated in Figs. 4 and 5. In this form the upper edges of said side walls 1^b are cut away to form continuous recesses 4^a which extend lengthwise of said body 1, said side walls 1^b being otherwise preferably entirely smooth and unbroken as in the first form of my improvement. The rear edge of the bottom in this form of my improved iron may also be curved as at 3 in the form first described. At its rear portion the said body is provided with projections 33 internally located at opposite sides and extending toward the apex 1^a for a distance from the rear wall 1^c of the body for the purpose to be more fully brought out hereinafter. If desired air inlet channels 34 may extend from the outer surface of the rear wall 1^c through said projections 33 so as to communicate with the interior of the body 1, although it is to be understood that these channels 34 are not absolutely necessary and may be omitted if desired. In the iron as shown in Figs. 6 to 10 inclusive the burner comprises a hollow shell or chamber 18^a adapted for connection with a source of fuel supply through the medium of the usual Bunsen tube 19 preferably detachably connected with said burner and extending outwardly through a suitable opening 21 in the rear wall 1^c as in the first form of my improvement, the said tube 19 being also provided with the customary nipple 20 for the accommodation of the usual flexible tubing or hose. In the form of my invention now being described the front face or wall 18^b of the shell or chamber 18^a is made integral therewith and is provided with a plurality of jet apertures 24^a projecting toward the apex, the said wall 18^b being preferably inclined or disposed at an angle as in the first form so that said apertures 24^a will also always be directed toward the inner surface of the bottom of the iron. In this form a confining plate 25^a is secured to or forms an integral part of the burner shell 18^a and has its major portion extending forwardly of said shell although as is shown in Fig. 7 the said plate also extends outwardly from the sides and rear thereof. The plate 25^a projects from said burner 18 at a point above the apertures 24^a and has its front end terminating at a distance from the apex 1^a to form a space α' , and is preferably provided with transversely extending lugs 25^b. The side edges of said plate 25^a are also preferably spaced, for at least a part of their length, from the side walls of the body to form spaces 26^a as is also clearly illustrated in Fig. 7. A screw 35 is in screw-threaded engagement with said plate 25^a and projects through the same for the purpose to be more clearly described hereinafter and is provided with an operating head 36. If desired the plate 25^a may be provided with an opening 37 located in close proximity to the burner 18^a and through which a match, taper or other igniting medium may be inserted for igniting the fuel at the jet apertures 24^a. When in position in the body 1 the burner 18^a rests upon the projections 33 which form a bearing therefor, the plate 25^a projecting toward the apex 1^a with the lower end of the screw 35 resting upon the inner surface of the bottom of the body and the tube 19 extending outwardly through the opening 21 of the rear wall 1^c. In this condition the combined burner 18^a and plate 25^a are supported in

4

operative position on the projections 33 and screw 35 as is clearly shown in Fig. 6 of the drawings. In order that the body 1 of this form of my improvement may be properly closed, I also provide the cover 5^a which is of proper size and shape to extend over and close the upwardly open body 1 and at the same time leave the recesses 4^a entirely free and unobstructed. To secure the said cover 10 5^a in position on the body 10 in such a manner that it may be moved relatively to the body in this form of iron I may provide a lug or projection 5^b which may be secured to or form an integral part of said cover 5^a 15 and depends therefrom near its apex. The front portion of the said lug 5^b is shaped to fit the recess 1^d formed by the inner surfaces of the side walls 1^b at the apex of the body and is inclined in the same direction 20 as is said apex, so that the lug 5^b and inner surface of the said apex will be in engagement when the cover is in its operative position. The rear end of the cover may be secured in position by means of a locking 25 lever 10 having shoulders 11 and 11^a and mounted in the same way as in Fig. 1 and coöperating with a slot 8 similarly formed in the cover 5^a. It will be evident that when the lever 10 is in the position shown in 30 Fig. 7 that the lug 5^b of the cover 5^a may be readily inserted into the said recess 1^d at the apex 1^a of the body 1 and the slot 8 passed over the lever 10 and shank 9 so as to permit the cover 5^a to be placed in 35 operative position. As the lever 10 is now moved in the direction of the arrow from the position in Fig. 7 to a position at approximately right angles thereto, the shoulders 11 and 11^a will be moved over the upper surface of the cover 5^a at opposite sides of the slot 8 in the manner previously described. The pressure which in this position is exerted by the shoulders 11 and 11^a will prevent the cover from being accidentally moved rearwardly a sufficient distance to disengage the lug 5^b from the recess 1^d at the apex of the iron. In order to still further guard against the accidental disengagement of the cover 5^a and to prevent any 45 looseness or rattling thereof I prefer to make the outer surface of the cover 5^a, at least adjacent to the slot 8 at its rear end, slightly curved or inclined in the manner indicated in Figs. 1 and 6. With this construction as the lever 10 is actuated in one direction or the other, for instance as described above, one or the other of the shoulders 11 and 11^a will engage this curved or inclined portion and exert a camming action thereon, so that as said lever 10 is brought to its locking position the cover 5^a will be cammed or forced forward and the lug 5^b will also be forced into close engagement with the inner surface of the apex 50 and into the recess 1^d formed thereby. In

this manner the cover 5^a in this form of my improvement is also firmly and rigidly secured in position against accidental displacement and against any looseness or rattling. 70

In the form at present being described the cover 5^a is provided with two preferably integral and spaced lugs 17^a projecting upwardly and having their free end portions reduced in diameter and arranged to 75 extend into correspondingly located sockets in the support 14^a, which consequently rests upon the shoulders formed by the largest portions of said lugs 17^a. Otherwise the handle arrangement and construction may 80 be the same as in the form shown in Figs. 1 to 5 inclusive. It will be seen, that with this arrangement the lugs 17^a prevent the support 14^a from rotating in a plane parallel with the surface plane of the cover or 85 in other words from swinging about the screw 15 as an axis and also serve to maintain said support substantially out of contact with the cover proper and thus reduce the transmission of heat from the cover, 90 through the support 14 to the handle 13 as in the first form described. It will of course be understood that under certain conditions one lug 17^a and coöperating socket 95 will be sufficient for the intended purpose and also if found preferable that the arrangement may be reversed, in which case the lug or lugs 17^a would be located on the support 14 and would coöperate with a socket or sockets formed in the cover 5^a. 100

When it is desired to use this form of iron, it is connected with a source of fuel supply in the same way as described with regard to the form of my improvement first described. The fuel passes through the tube 105 19 into the shell or burner chamber 18^a and out through the apertures 24^a where it may be ignited in any suitable manner as by passing a lighted match, taper or other igniting medium through the opening 37. This opening 37 may be omitted if desired and the fuel simply permitted to enter the body 1 for a short period and then ignited either at the space a' or the spaces 26^a. After being ignited the flames at the jet apertures 110 24^a will be directed toward the apex and bottom owing to the direction in which said apertures project and the inclination of the wall 18^b and may even be deflected toward said bottom by the plate 25^a, which latter 115 serves to confine the heat from said flames in close proximity to said bottom and thus prevents indiscriminate spreading and loss of said heat and in consequence insures a rapid heating of the iron and the maintenance of said heated condition throughout the period of use of said iron. If the air inlets 34 form part of the structure air will 120 pass through the same to the flames at the burner; it has been found however that these 130

air inlets are not absolutely necessary and that a sufficient amount of air will pass through the recesses 4^a, and spaces a' and 26^a and even through the opening 37, if this 5 is used, to said flames. Substantially perfect combustion is secured in either case without the need of any additional air inlets. By rotating the screw 35 the inclination of the plate 25^a relatively to the bottom 10 of the iron is adjusted to bring the lugs 25^b into engagement with the side walls 1^b whereby said plate, the shell or burner chamber 18 and the tube 19 are firmly secured in position. The said plate 25^a thus confines 15 the heat in the space beneath it and also directs said heat along the bottom so that all parts thereof will be directly influenced thereby. It will be noted that the front face of the burner is preferably flat and of 20 considerable extent in both forms of my invention so that a burner having a maximum heating action is secured and jets or flames of maximum effect are provided. It will further be seen that in the form of my 25 improvement illustrated in Figs. 6 to 10 inclusive the lugs 25^b through contact with the inner surfaces of the upwardly converging side walls 1^b at a certain point limit the upward adjustment of the plate 25^a and 30 prevent excessive actuation of the screw 35 and complete removal of the forward end of said plate from the body.

The burner and its connected parts in said last form may be readily removed from 35 the body when this is desired, by simply first removing the cover 5^a, then disconnecting the tube 19 and then tilting one longitudinal edge upwardly, in which condition said burner and its parts are easily taken 40 from the said body.

It will further be apparent that the members 25 and plate 26 may be combined with the shell 18^a of Fig. 6 or that the plate 25^a and screw 35 of said Fig. 6 may be combined with the shell 18 of Fig. 1. The projections 33 and air channels 34 may also be introduced into the form of my improvement first described if this should be desired or found advisable.

50 It will be seen that in both forms my iron is extremely simple in construction, the body thereof being merely an upwardly open shell absolutely unbroken except for the upper recesses 4 and 4^a and adapted to removably 55 and adjustably receive the burner which itself is extremely simple in construction in both forms. An iron constructed in accordance with either form of the present invention

tion will operate in a maximumly effective manner and may be easily adjusted to so 60 operate under all conditions and with all grades of gaseous fuel.

By curving the rear edge of the bottom of the iron as shown at 3 the said edge may be introduced into folds or creases and the 65 body of the iron oscillated by means of the handle thus facilitating the ironing of the fabric beneath such folds or in the creases, the curved edge 3 rolling along said folds or creases as it were during this operation. 70

Various changes in the specific form shown and described may be made within the scope of the claims without departing from the spirit of my invention.

I claim:

1. A self-heating sad iron comprising a hollow body, a burner therein having an apertured face extending transversely to the longitudinal axis of said body, a pair of connected members extending from said burner for supporting same and forming a substantially horizontal opening in front of said apertured face, a movable cover for said body and a closure carried by said cover and arranged to fit in said opening whereby the 80 heat from the burner is confined adjacent to the bottom of said body.

2. A self-heating sad iron comprising a hollow body, lugs in said body near the apex thereof, a projection extending upwardly 90 from said body and converging toward the rear thereof, a cover for said body, a burner in said body having an apertured face extending transversely to the longitudinal axis thereof, members extending from said burner 95 parallel with the side walls of said body and arranged to rest upon said lugs whereby said burner is supported in position, a plate connecting the free ends of said members and provided with a slot, a screw extending through said slot into engagement with said projection whereby said burner is secured against removal from said body, said members and plate forming a substantially horizontal opening in front of said apertured 100 plate, and a closure depending from said cover and adapted to fit into said opening whereby the heat from said body is confined 105 adjacent to the bottom of said body.

In testimony whereof I have hereunto set 110 my hand in the presence of two subscribing witnesses.

CHARLES STICHLER.
